(57) **CLAIM**

The ornamental design for a navigation device, as shown
and described.

DESCRIPTION

FIG. 1 is a perspective view of a navigation device showing
our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view.

The broken line showing in FIG. 1 to 7 is for illustrative
purposes only and forms no part of the claimed design.
